BOILER

Charles W. Brabbée, Tuckahoe, and Bernhard Goerg, Bronxville, N. Y., assignors to American Radiator Company, New York, N. Y., a corporation of New Jersey

Application April 1, 1936, Serial No. 72,006

4 Claims. (Cl. 122—218)

Our invention relates to improvements in heating apparatus and the same has for its objects generally to provide a boiler for heating buildings or other structures which is simple in construction, easy to operate, and efficient in performance.

Further, said invention has for its object to provide a boiler for economically and efficiently burning liquid fuel.

Further, said invention has for its object to provide a boiler which is compact in form, and of relatively small dimension compared to its output, and of convenient size for transportation.

Further, said invention has for its object to provide an oil burning boiler in which the fuel may be easily and quickly ignited to start combustion.

Further, said invention has for its object to provide a boiler in which the burner and the means for supporting the same may be readily introduced into the combustion chamber and fire pot of the boiler without necessitating the dismounting or taking apart of the boiler.

Other objects will in part be obvious and in part be pointed out hereinafter.

To the attainment of the aforesaid objects and ends our invention consists in the novel features of construction, and in the combination, connection and arrangement of parts hereinafter more fully described and then pointed out in the claims.

In the accompanying drawings—

Figure 1 is a front elevation showing one form of oil burning boiler constructed according to and embodying our said invention, the front wall 35 of the enclosing jacket being removed to expose the boiler proper;

Fig. 2 is a vertical section on the line 2—2 of Fig. 1, and

Fig. 3 is a transverse section on the line 3—3 of Fig. 2.

In said drawings 10 designates the boiler as a whole comprising a jacket 11 including a front section 12, a back section 13, side sections 14, and a top section 15, all of which are secured together along their abutting edges by keys 16 to form a complete enclosure. The front section 12 is provided with a large, rectangular opening 17 provided with a removable closure panel 18, maintained in position to close said opening by clips or ears 19 at the lower edge of said panel engaging with said front section 12 adjacent the lower edge of said opening, and by spring-actuated detents 20, adapted to engage with the front section adjacent to the upper edges of said opening.

21 denotes a similar but smaller rectangular

opening yielding access to the interior of the base of the boiler, and 22 denotes a closure fitting into said opening 21, and secured in position therein by suitable fastening devices, such as spring actuated detent 23.

Within the jacket 11 is disposed a vertical sectional boiler 24 comprising a hollow cast metal base section 25 having a large front opening 26, and smaller openings 26a in its sides and rear wall portions. The upper portion of said section 25 is provided with an elliptical opening corresponding in size substantially with the interior opening or outline of the fuel receptacle and combustion chamber supported thereon, as herein-after described.

27 denotes the fire pot or fuel receptacle and combustion chamber section which is more or less elliptical in external contour and provided with a flattened front portion 27a. The interior space of the said section 27 is substantially elliptical in cross-section and corresponds generally with the opening of the base section 25. The said fire pot and combustion chamber section 27 is provided at its lower outer edge with lugs 28 fitting into recesses 29 in the base section 25, and secured thereto by bolts 30 extending through said lugs 28 and into the top of said base section 25. The inner lower edge of said section 27 is recessed at 31 to form an elliptical overhanging rim 32.

The front of said fire pot section 27 is provided with an opening 33 having a closure 34 fitting into the same and supported in place by spring-pressed clips 35 engaging recessed portions 36 at the corners of said closure 34 which, while serving to maintain the said closure 34 in position normally to seal said opening 33 will, nevertheless, permit said closure to yield outwardly should any undue pressure develop in the fire pot 27, and thus relieve said excess pressure.

The closure 34 is also provided with a sight opening 37 covered by a section of glass 38, protected from the heat and flame within the furnace by a metal shutter 39 disposed to the rear of said glass section 38, and movably supported upon a slide 40 working in a horizontal slot 41 provided in said closure 34. The slide 40 and shutter 39 may be actuated by a finger portion 40a secured to and extending outwardly from slide 40.

42 denotes the intermediate boiler section which corresponds in outline with the fire pot or fuel receptacle and combustion chamber section 27, and is communicatively connected therewith by nipples 43, 44. The upper side intermediate section 42 is concaved or dished and provided with series of longitudinal, transversely-inter-

rupted fins 45 extending from the front to the rear portion of the section, and tapering in height from the center portion to the edges of the section. The said fins 45 have their upper 5 edges disposed in the same horizontal plane, and a short distance vertically below the edge or rim of said intermediate section 42. The underside of said intermediate section is depressed at its forward portion to form a recessed dome 46 for 10 the fuel receptacle and combustion chamber 27, and is also formed with a relatively deep water-backed rear portion 47. The bottom wall of said intermediate section, within the recessed portion 46 thereof, is provided with shallow corrugations 15 or wave-like portions 48, which extend from the front towards the rear of the section in order to allow for expansion and to increase the surface area thereof exposed to the hot gases and radiant heat of the fuel.

20 The deep rear portion 47 of said intermediate section is provided with two arc-shaped vertical openings constituting water-backed flues 49 provided with vertical fins 49^a which taper towards their lower ends.

25 50 denotes the relatively deep dome or top section which corresponds in outline with the intermediate section 42, and is communicatively connected therewith by nipples 51, 52, corresponding in position to the positions of the 30 nipples 43, 44, connecting the intermediate section 42 with the fire pot section 27. The underside of said dome section is provided with corrugations 53 extending from the forward to the rear part of the section, and said corrugated surfaces 35 are provided with depending series of longitudinal, transversely interrupted fins 53^a which extend in a direction parallel to said corrugations 53, and register in vertical planes with the upwardly extending fins 45 on the upper side of the 40 intermediate section 42. Adjacent to its forward end said dome section 50 is provided with an arc-shaped opening 54 constituting a flue, communicating at its upper end with a relatively wide, shallow, horizontal flue 55 extending rearwardly 45 through the water space of said section and having a flaring rear end forming a smoke outlet 55^a communicating with the smoke-hood 56. The vertical wall of said opening 54 is provided with fins 57, and the upper side or wall portion of said 50 horizontal flue 55 is provided with corrugations 57^a extending from the front to the rear part of the section, and provided with parallel series of interrupted fins 58 which register with corresponding interrupted fins 59 provided upon the 55 lower side or wall portion of said horizontal flue 55.

The front of said dome section 50 is provided with a clean-out opening 60 which is formed entirely within said section and water-backed 60 along its edges thereby, and provided with a closure 61 yieldingly maintained in position by spring-pressed latches 62 pivotally secured to the front of the dome section.

63 denotes the flow pipe extending from the 65 top of the dome section 50, and 64 the return pipe connected to the water space of the fire pot section 27 adjacent to the lower end of said section.

Within the fire pot section 27 is disposed a 70 hearth ring 65 having a short, inwardly-extending flange 66 at its base, and a relatively deep upwardly extending vertical flange 67 at its top whose free end extends into the recess 31 of the fire pot section 27, and has its edge beveled inwardly and downwardly at 68. The hearth ring 75

65 is secured to the top of the base section 25 by bolts 69 extending through slots 70 in said base section. To form a fluid tight joint between the hearth ring 65 and the base 25, washer 71 of asbestos or other suitable material is interposed 5 between said parts.

The different forms of oil burners call for different constructions of hearth. In the accompanying drawings one illustrative construction is shown, in which 72 denotes a metal hearth- 10 plate supported at its edge upon the flange 66 of the hearth ring 65. Upon said hearth plate 65 is supported a refractory covering 72^a provided with a recessed or depressed central portion 72^b and a central opening 73 therein to receive an oil 15 burner indicated by broken lines at 74. The refractory covering is provided inwardly of its periphery with an annular ridge 75, and between said ridge and the outer edge of said refractory covering 72^a are disposed a series of segmental 20 tiles 76 forming a wall at the outer edge of said covering 72^a. Each of said tiles 76 has a concave recess or groove portion at its base, which with the recesses of the adjacent tiles, form an oil pocket or groove 77. At the inner edge of said 25 tiles 76 are provided a series of upwardly extending fingers 78. The spaces between said fingers form passages 78^a through which air may pass and mix with the oil vaporized in the pocket or groove 77 to form the combustible heating me- 30 dium. Any oil which fails to reach the groove 77 will be retained upon the refractory lining 72^a by the ridge 75 and there be vaporized and consumed.

Having thus described our said invention what 35 we claim and desire to secure by Letters Patent is:

1. A boiler of the character described includ- 40 ing a base section having a central opening therein and a fire pot section supported on said base section; said fire pot section having a recessed inner lower edge, a hearth ring secured to said base section having an inwardly-extending flange at its base and a vertical wall portion extending into said recessed edge of the fire pot section, and a hearth plate supported upon the inwardly-ex- 45 tending flange of said hearth ring.

2. A boiler of the character described includ- 50 ing a base section having an opening at its top, and a fire pot section supported on said base sec- 55 tion, said fire pot section having a central open- 60 ing at its bottom conforming to the opening in said base section, and a recess along the edge of the opening in said fire pot section, an annular support secured to said fire pot section along the opening therein and having its upper edge ex- 65 tending into said recess, and a hearth plate mounted on said annular support.

3. A boiler of the character described includ- 70 ing a base section having an opening at its top, and a fire pot section supported on said base sec- 75 tion, said fire pot section having a central open- 80 ing at its bottom conforming to the opening in said base section, and a recess along the edge of the opening in said fire pot section, an annular support secured to said base section along the 85 opening therein, an annular wall extending up- 90 wardly from said annular support and having its upper edge extending into said recess, a hearth plate mounted on said annular support, and a refractory covering on said hearth plate; said 95 hearth plate and said refractory covering having registering openings therein to receive an oil burner.

4. A boiler of the character described includ- 100 ing a base section having an opening at its top, 75

and a fire pot section supported on said base section, said fire pot section having a central opening at its bottom conforming to the opening in said base section, and a recess along the edge of the opening in said fire pot section, an annular support secured to said base section along the opening therein, an annular wall extending upwardly from said annular support and having its upper edge extending into said recess, a hearth plate mounted on said annular support, a refractory covering on said hearth plate; said hearth

plate and said refractory covering having registering openings therein to receive an oil burner; said refractory covering having an annular recess adjacent its edge, and a series of segmental refractory tiles disposed upon said refractory covering intermediate the edge thereof and said annular recess, and said tiles each having a portion terminating in upwardly extending fingers. 5
